Attorney.

UNITED STATES PATENT OFFICE.

FRANCIS B. HALL, OF BRYN MAWR, PENNSYLVANIA.

COMBINATION RIDING TROUSERS AND BREECHES.

1,405,114.

Specification of Letters Patent. Patented Jan. 31, 1922.

Application filed March 22, 1921. Serial No. 454,450.

To all whom it may concern:

Be it known that I, FRANCIS B. HALL, a citizen of the United States, residing at Bryn Mawr, in the county of Montgomery and State of Pennsylvania, have invented certain new and useful Improvements in Combination Riding Trousers and Breeches, of which the following is a specification.

My invention relates to combination riding trousers and breeches, and it relates more particularly to an improved construction of the lower leg portions thereof.

The principal object of my invention is to provide a garment suitable to be worn either as riding trousers or as breeches, as desired by the wearer. A further object thereof is to provide in a garment of this character, a construction of the lower leg portions thereof whereby there will be provided a close fitting arrangement, having a suitable cuff when worn as trousers, which cuff may, however, be dispensed with when the garment is worn as breeches, and which is so arranged that the garment may be readily put on by the wearer with a minimum of discomfort, but which will at all times present a neat and satisfactory appearance.

My invention, therefore, contemplates a construction of the lower leg portion of the garment whereby the same may be worn as breeches in connection with the usual leggings, puttees, boots or stockings, presenting, when so worn, no objectionable thickness of any of the parts which would cause an unsightly appearance or discomfort to the wearer, yet being characterized by the above mentioned facility and convenience in being put on and taken off by the wearer.

The nature and characteristic features of my invention will be more readily understood from the following description, taken in connection with the accompanying drawings forming part hereof, in which—

Figure 1 is a perspective view of a pair of combination riding trousers and breeches embodying the main features of my present invention;

Figs. 2 and 3 are side and front elevational views, respectively, of the lower leg portion of the garment, certain parts being partly opened up to more clearly illustrate the details of the construction and arrangement; and

Fig. 4 is an underneath plan thereof.

Referring to the drawings, the combination trousers and breeches 5 may, in their

upper portions, be made in any desired shape or style, but as the same are particularly designed for riding and other athletic pursuits, they are usually cut and formed full in the hip portions to afford a maximum of comfort for the wearer when used for such purposes. The lower leg portions 6, however, are preferably made form-fitting, and at the lower end of each of said lower leg portions, there is provided a vent or open seam 7, extending a short distance upward from the lower end.

Adjacent the lower end of the lower leg portion, there is provided a series of buttonholes 8, which are provided for the purpose of attaching thereto a detachable cuff member 9, by means of complementally located buttons 10, which buttons are mounted on the inner face of the cuff member 9. The cuff member 9 is adapted to encircle the lower end of the lower leg portion 6 so as to afford a neat and pleasing finish and to provide the trousers effect thereto.

The cuff member 9 is preferably made so as to have an adjustable girth, and for such purpose, one end of the cuff member may be provided with suitable strap eyes 11, which are adapted to be engaged by straps 12 carried by the cuff member 9 near the other end thereof, and suitable buckles 13 are also provided so that, when the straps are passed through the eye members 11 and brought back, the straps 12 may engage the buckles 13 to thereby provide means for adjustably varying the girth of the cuff member 9. It will, of course, be understood that other alternative means for connecting the ends of the cuff members may be provided, when desired.

It will be noted that in order to provide a sufficient opening at the lower end of the close fitting lower leg portion 6, to permit the wearer's foot to be passed therethrough, the vent 7 should extend some distance upward from the bottom thereof, and for the purpose of maintaining this vent normally closed, when the garment is worn as trousers with the cuff 9 attached, the top flap 14 of the vent portion is provided with a suitable lacing member 15, preferably made of cord in the form of a loop, and having one end securely attached to the inner face of the top flap 14 of the vent 7 near the upper end thereof. The under flap 16 of the vent portion is provided with two eyelets 17 and 18, and the top flap 14 is also provided, near

its lower end, with an opening in the form of a button-hole 19. The lacing member 15 is adapted to be passed through the upper eyelet 17 to the inside, thence through 5 the lower eyelet 18 to the outside of the inner flap 16, thence through the opening 19 in the top flap 14, and is then adapted to be looped over a button 20 mounted on the inner face of the cuff member 9 near the lower 10 margin thereof.

By the foregoing arrangement, when the garment is to be worn as trousers, the lacing member 15 will be passed through the eyelets 17 and 18 and opening 19, as above set 15 forth, and then looped over the button 20 of the cuff 9, after the garment is in position on the wearer, after which the straps 12 are passed through the strap eyes 11, and the straps 12 are then brought into engagement 20 with their respective buckles 13, being tightened sufficiently to maintain the lower end of the leg portion of the assembled garment in close conformity to the leg of the wearer. When so arranged, the lacing device 25 15 will effectively maintain the upper portion of the vent 7 of the cuff member 9 securely closed at all times, the vent 7 and the adjustable arrangement of the cuff 9 permitting variations in the girth of the lower 30 end within desirable limits.

When it is desired to use the garment as breeches, that is, in connection with riding boots, leggings, puttees or stockings, the cuff member 9 may be dispensed with, while 35 the garment is being so worn, and it will be noted that there will be no objectionable buttons or other parts of such appreciable dimensions as to cause any discomfort to the wearer, or unsightly appearance of the 40 superimposed apparel, such as the boots, leggings, puttees or stockings.

It will be seen that there is thus provided a garment, the lower leg portion of which is of novel construction whereby the garment 45 is adaptable for a variety of uses, which may be conveniently put on and taken off, which at all times may be worn with comfort by the wearer, and which will, in any of its intended uses, present a neat, satisfactory and desirable appearance.

Having thus described the nature and characteristic features of my invention, what I claim as new and desire to secure by Letters Patent, is:

55 1. A garment having lower leg portions each having a vent or open seam extending upwardly a short distance from the bottom thereof, a separate cuff member, means for attaching said cuff member to the lower end 60 of said leg portion, and means for maintaining the vent in the leg portion closed comprising a lacing device having one end attached to the inner face of the outer flap of the vent, thence passing through suitable 65 eyelets in the inner flap of the vent, and

thence passing through an opening at the lower end of the outer flap thereof, and a button carried on the inner face of the cuff member over which said lacing device is looped. 70

2. A garment having lower leg portions each having a vent or open seam extending upwardly a short distance from the bottom thereof, a separate cuff member, means for attaching said cuff member to the lower end 75 of said leg portion, means for securing the ends of the cuff member to each other, and means for maintaining the vent in the leg portion closed comprising a lacing device having one end attached to the inner face 80 of the outer flap of the vent, thence passing through suitable eyelets in the inner flap of the vent, and thence passing through an opening at the lower end of the outer flap thereof, and a button carried on the inner 85 face of the cuff member over which said lacing device is looped.

3. A garment having lower leg portions each having a vent or open seam extending upwardly a short distance from the bottom 90 thereof, a separate cuff member, means for attaching said cuff member to the lower end of said leg portion, means for adjustably securing the ends of the cuff member to each other, and means for maintaining the vent 95 in the leg portion closed comprising a lacing device having one end attached to the inner face of the outer flap of the vent, thence passing through suitable eyelets in the inner flap of the vent, and thence passing 100 through an opening at the lower end of the outer flap thereof, and a button carried on the inner face of the cuff member over which said lacing device is looped.

4. A garment having lower leg portions 105 each having a vent or open seam extending upwardly a short distance from the bottom thereof, a separate cuff member, means for attaching said cuff member to the lower end of said leg portion, strap and buckle means 110 for adjustably securing the ends of the cuff member to each other, and means for maintaining the vent in the leg portion closed comprising a lacing device having one end attached to the inner face of the outer flap 115 of the vent, thence passing through suitable eyelets in the inner flap of the vent, and thence passing through an opening at the lower end of the outer flap thereof, and a button carried on the inner face of the cuff 120 member over which said lacing device is looped.

5. A garment having lower leg portions each having a vent or open seam extending upwardly a short distance from the bottom 125 thereof, and provided with a series of buttonholes, a separate cuff member having buttons complementary to said buttonholes for attaching said cuff member to the lower end of said leg portion, strap and buckle means 130

- for adjustably securing the ends of the cuff each having a vent or open seam extending upwardly a short distance from the bottom thereof, a separate cuff member, means for attaching said cuff member to the lower end 45 of said leg portion, means for adjustably securing the ends of the cuff member to each other, and means for maintaining the vent in the leg portion closed comprising a lacing device operatively connecting the flaps of 50 the vent and the cuff member.
- 5 5. A garment having lower leg portions each having a vent or open seam extending upwardly a short distance from the bottom thereof, thence passing through suitable eyelets in the inner flap of the vent, and thence passing through an opening at the lower end of the outer flap thereof, and a 10 button carried on the inner face of the cuff member over which said lacing device is looped.
6. A garment having lower leg portions each having a vent or open seam extending 15 upwardly a short distance from the bottom thereof, and provided with a series of buttonholes, a separate cuff member having buttons complementary to said buttonholes for attaching said cuff member to the lower end 20 of said leg portion, means for adjustably securing the ends of the cuff member to each other, and means for maintaining the vent in the leg portion closed operatively connected to the cuff member.
- 25 7. A garment having lower leg portions each having a vent or open seam extending upwardly a short distance from the bottom thereof, and provided with a series of buttonholes, a separate cuff member having buttons complementary to said buttonholes for 30 attaching said cuff member to the lower end of said leg portion, strap and buckle means for adjustably securing the ends of the cuff member to each other, and means for maintaining the vent in the leg portion closed comprising a lacing device having one end attached to one of the flaps of the vent, passing through suitable 35 openings in the other flap of the vent, and looped over a button carried on the inner face of the cuff member.
- 40 8. A garment having lower leg portions
6. A garment having lower leg portions each having a vent or open seam extending upwardly a short distance from the bottom thereof, a separate cuff member, means for attaching said cuff member to the lower end 55 of said leg portion, means for adjustably securing the ends of the cuff member to each other, and means for maintaining the vent in the leg portion closed comprising a lacing 60 device having one end attached to one of the flaps of the vent, passing through suitable openings in the other flap of the vent, and operatively connected to the cuff member.
7. A garment having lower leg portions each having a vent or open seam extending upwardly a short distance from the bottom thereof, a separate cuff member, means for attaching said cuff member to the lower end 65 of said leg portion, means for adjustably securing the ends of the cuff member to each other, and means for maintaining the vent in the leg portion closed comprising a lacing device having one end attached to one of the flaps of the vent, passing through suitable 70 openings in the other flap of the vent, and looped over a button carried on the inner face of the cuff member.
8. A garment having lower leg portions each having a vent or open seam extending upwardly a short distance from the bottom thereof, a separate cuff member, means for attaching said cuff member to the lower end 75 of said leg portion, means for adjustably securing the ends of the cuff member to each other, and means for maintaining the vent in the leg portion closed comprising a lacing device having one end attached to one of the flaps of the vent, passing through suitable openings in the other flap of the vent, and looped over a button carried on the inner face of the cuff member.

In testimony whereof, I have hereunto signed my name.

FRANCIS B. HALL.
